(57) **CLAIM**

The ornamental design for a laser head, as shown and described.

DESCRIPTION

FIG. 1 is a front perspective view of a laser head design showing my new design.

FIG. 2 is a front view of a laser head.

FIG. 3 is a rear view of a laser head.

FIG. 4 is a left side view of a laser head.

FIG. 5 is a right side view of a laser head.

FIG. 6 is a top view of a laser head.

FIG. 7 is a bottom view of a laser head.

FIG. 8 is a rear perspective view of a laser head; and, FIG. 9 is a perspective view thereof, showing the laser head with protective sleeve.

The broken lines depict portions of the laser head that form no part of the claimed design.
